UNITED STATES PATENT OFFICE.

BERT ARTHUR LINDERMAN, OF CHICAGO, ILLINOIS.

DESIGN FOR A CABINET FOR AN ELECTRICAL POWER PLANT.

57,078.

Specification for Design.

Patented Feb. 8, 1921.

Application filed May 19, 1920. Serial No. 382,609. Term of patent 14 years.

To all whom it may concern:

Be it known that I, BERT ARTHUR LINDERMAN, a citizen of the United States, residing at Chicago, in the county of Cook and State of Illinois, have invented a new and ornamental Design for Cabinets for Electrical Power Plants, of which the following is a specification, reference being had to the accompanying drawings forming part thereof.

The figure is an elevation in perspective illustrating a cabinet for a domestic power plant.

I claim:—

The ornamental design for a cabinet for an electrical power plant, as shown.

BERT ARTHUR LINDERMAN.
